POPPET VALVE-ACTUATING MECHANISM

Galen H. Peters, Los Angeles, Calif.

Application May 29, 1944, Serial No. 537,776

1 Claim. (Cl. 123—90)

This invention relates to poppet valve-actuating mechanism, and more particularly to improvements in the cam construction for actuating the poppet valves of an internal combustion engine.

The general object of the invention is to provide an improved cam construction which makes it unnecessary to overcome spring tension in opening the poppet valves of an internal combustion engine.

A more particular object is to provide an improved cam construction of the character stated for positively opening and closing the poppet valves of an internal combustion engine.

Another object is to provide a cam construction for actuating the poppet valves of an internal combustion engine by means of which said valves are put under spring tension by the actuating cams at their lowermost position for holding said valves closed firmly upon their seats.

A further object is to provide a cam construction of the character stated, by means of which the poppet valves, actuated by the cams of said construction, are free when lifted off their seats to turn in their bearings and wear evenly on their seats.

Other objects and advantages will appear hereinafter.

The invention is illustrated in the annexed drawing, which forms a part of this specification, and in which:

Fig. 1 is a fragmentary transverse vertical section of an internal combustion engine, showing one of the poppet valves of the engine and my improved cam construction for actuating said valve, which is shown closed.

Fig. 2 is a fragmentary longitudinal vertical section of the internal combustion engine shown on Fig. 1, showing two of the poppet valves of the engine and my improved cam construction for actuating the same, one of said valves being shown closed and the other valve being shown open.

Fig. 3 is a sectional view of my improved cam construction for actuating the poppet valves shown in Fig. 1 and taken on line 3—3 thereof.

Fig. 4 is a fragmentary elevation of the stem of the closed valve shown in Figs. 1 and 2, the tappet for actuating said valve, and the spring of my cam construction connecting said valve stem and said tappet, the tappet being drawn down slightly below the valve stem by my cam construction, further expanding said spring whereby said valve is held firmly closed upon its seat.

Fig. 5 is a fragmentary elevation of the stem of the open valve shown in Fig. 2, the tappet lifting said valve, and the spring of my cam construction connecting said valve stem and said tappet, the tappet being raised by said cam construction and said spring being contracted slightly, whereby the upper end of said tappet engages the lower end of said valve stem and raises and opens said valve.

10 Fig. 6 is a horizontal cross section of the stem of the closed valve shown in Figs. 1 and 2 taken on line 6—6 of Fig. 4 and showing the connection of the upper end of the spring of my cam construction to said valve stem.

15 Fig. 7 is a horizontal cross section of the tappet of the open valve shown in Fig. 2, taken on line 7—7 of Fig. 5 and showing the connection of the lower end of the spring of my cam construction to said tappet.

20 Referring more particularly to the drawing, in which corresponding parts are designated by the same reference characters in all of the figures, 1 designates a poppet valve of an internal combustion engine 2, and 3 designates my novel cam-actuating mechanism for said poppet valve, which mechanism is suitably mounted on said engine.

The poppet valve 1 comprises a valve head 4 and a valve stem 5 depending from said head and slidably mounted in a valve guide bushing 6, so that said valve head may be moved down upon its seat 7 to close the valve, or lifted above its seat to open the valve, in the manner hereinafter more fully described. The poppet valve 1 controls communication between a fuel-inlet or exhaust port 8 and a combustion chamber 9 of an internal combustion engine 2.

My cam-actuating mechanism 3 includes a conventional valve-opening cam 10 and a pair of valve-closing cams 11, a yoke 12 fitted over and engaged by said cams, a plunger 13, turnably connected at its lower end to said yoke and extending upwardly therefrom, a tappet 14 adjustably connected to said plunger and extending upwardly therefrom, and a coil spring 15 surrounding the upper portion of said tappet 14 and the lower portion of the valve stem 5 which spring is expanded to a predetermined tension, and is connected at its ends to said tappet and said valve stem, respectively, in the manner hereinafter more particularly described. The cams 10 and 11 are secured on the conventional cam shaft 16 of the engine 2, with the cams 11 suitably spaced apart and the cam 10 positioned midway between said cams 11. The yoke 12 comprises a pair of guide rods 17 and a pair of cross-bars 18 and 19.

The cross bar 18 is adjustably secured at its ends on the lower ends of said guide rods 17, respectively, by nuts 20 and 21 threaded on said rods, and the cross bar 19 is adjustably secured at its ends on said guide rods, respectively, above the cross bar 18 by nuts 22 and 23 threaded on said rods, with the cross bar 18 adjacent the lower edges of the cams 10 and 11, and the upper cross bar 19 adjacent the upper edge of the cam 10. The guide rods 17 extend upwardly above the cross bar 19 and the upper portions of said rods are slidably fitted in guide bearings 24 depending from a horizontal wall 25 of the engine 2, whereby the yoke 12 is mounted to be reciprocated up and down by the cams 10 and 11 for opening and closing the poppet valve 1, in the manner hereinafter more fully described. The cross bar 19 is provided with an opening 26 therein midway between its ends, through which openings extends the lower end of the tappet plunger 13, which end of said plunger rests upon the upper edge of the cam 10 and is formed with an external annular flange 27, which is countersunk in the lower surface of said cross bar 19 in an annular enlargement 28 of the lower end of said opening 26 in said cross bar, which enlargement forms an annular shoulder 29, in said cross bar, engaged by the upper surface of said annular flange 27 of said plunger 13, in the manner and for the purpose hereinafter more fully described, said plunger 13 and its said flange 27 being turnably fitted in the opening 26 and its enlargement 28, respectively, in the cross bar 19, so that the poppet valve 1 may turn at all times. The tappet plunger 13 extends upwardly from the cross bar 19 of the yoke 12 through a guide bearing 30 depending from the wall 25 of the engine 2, and is formed with a threaded bore 31 in its upper end portion, in which bore is threaded the lower threaded end portion 32 of the tappet 14, the upper end 33, of which tappet extends adjacent the lower end 34 of the valve stem 5. On the tappet 14, intermediate its ends, is formed a hexagonal surface 35 to be gripped by a wrench for turning the tappet in threaded engagement with the threaded bore 31 of the plunger 13, whereby the tappet is adjusted longitudinally up or down with relation to said plunger to increase or decrease its length above the upper end of said plunger. A lock nut 36 is threaded on the tappet 14 below the hexagonal surface 35 for engaging the upper end of the plunger 13 for locking the tappet 14 in longitudinally adjusted positions with relation to said plunger. The coil spring 15, surrounding the upper portion of the tappet 14 and the lower portion of the valve stem 5, is detachably connected to said tappet and said valve stem by clamps 37 and 38, respectively, on the lower end and upper end of said spring. The clamp 37 comprises a yoke 39 and a screw bolt 40 and nut 41, which yoke is formed by the lower end of the spring 15 bent U-shape transversely of the spring and in the form of eyes 42 and 43 at the ends, respectively, of said yoke, through which eyes extend said bolt 40, with the head 44 of said bolt engaging said eye 42 and said nut 41 threaded on the end of said bolt, engaging said eye 43. The yoke 39 straddles the tappet 14 and is fitted in an annular groove 45 in the periphery of said tappet, with the ends of said yoke projecting transversely beyond the side of said tappet, opposite its side which is engaged by the intermediate portion of said yoke in said groove 45 and with the screw bolt 40 extending tangentially through said groove 45 between the ends 75

5 of the yoke. The clamp 38 comprises a yoke 46 and a screw bolt 47 and nut 48 which yoke is formed by the upper end of the spring 15 bent U-shape transversely of the spring, and in the form of eyes 49 and 50 at the ends respectively, of said yoke through which eyes extends said screw bolt 47 with the head 51 of said bolt engaging said eye 49 and said nut 48 threaded on the end of said bolt, engaging said eye 50. The yoke 46 straddles the valve stem 5, and is fitted in an annular groove 52 in the periphery of said valve stem, with the ends of said yoke projecting transversely beyond the side of said valve stem opposite its side, which is engaged by the intermediate portion of said yoke in said groove 52 and with the screw bolt 47 extending tangentially through said groove 52 between the ends of said yoke.

20 The operation of my invention is as follows:

Assuming the poppet valve 1 to be closed and my cam-actuating mechanism 3 to be in its lowermost position, as shown in Fig. 1, and as shown by the valve 1 and my actuating mechanism 3 at the left of Fig. 2 of the drawing; rotation of the cam shaft 16 and the cams 10 and 11 upon operation of the engine 2, causes the high point 53 of the cam 10 to engage the lower end of the plunger 13 and lift said plunger and the tappet 14 sufficiently to cause the upper end of said tappet to engage the lower end of the valve stem 5 and lift the valve 1 until the valve head 4 is lifted off its seat 7 and the valve is opened, during which operation the upper surface of the annular flange 27, on the lower end of the plunger 13, engages the annular shoulder 29 in the cross bar 19 of the yoke 12 and lifts said yoke to its uppermost position while the low points 54 of the cams 11 are brought to their lowermost position above the cross bar 18 of said yoke to permit said yoke to be lifted as aforesaid, and as illustrated by the valve 1 and my valve-actuating mechanism 3 at the right of Fig. 2 of the drawing. As the cams 10 and 11 are further rotated the high point 53 of the cam 10 is rotated away from the lower end of the plunger 13, and the low point 55 of said cam is brought under said end of said plunger, while the low points 54 of the cams 11 are rotated away from the lower cross bar 18 of the yoke 12 and the higher points of said cams 11 are rotated against said cross bar 18, whereupon the yoke 12 is drawn downwardly and the shoulder 29 in the cross bar 19 of said yoke, engaging the upper surface of the annular flange 27 on the lower end of the plunger 13, causes said plunger and tappet 14, spring 15 and the valve stem 5 and head 4 to be drawn down positively by the cams 11 until said valve head 4 engages its seat 7, and as the highest points 56 of said cams 11 directly engage the yoke cross bar 18 the yoke 12, the plunger 13 and tappet 14 are drawn further downwardly a slight distance against the tension of the spring 15 until the upper end of said tappet is drawn down a slight predetermined distance below the lower end of the valve stem 5, whereupon the spring 15 is expanded slightly and a downward force, under the tension of said spring is applied to the valve stem 5 and head 4, and said valve head is drawn down with greater force against its seat 7, and the valve 1 is more firmly and effectively seated and closed, as shown in Fig. 1 and as illustrated by the valve 1 and my cam-actuating mechanism 3 at the left of Fig. 2 of the drawing.

70 I claim:

75 In combination with a poppet valve and the

cam shaft of an internal combustion engine, a valve-opening cam and a valve-closing cam on said cam shaft, a plunger and a tappet connected to the upper end of said plunger arranged with the lower end of said plunger resting upon said valve-opening cam and the upper end of said tappet extending adjacent the lower end of the stem of said poppet valve, a reciprocative yoke including a lower cross bar, engaged by said valve-closing cam, and an upper cross bar to which the lower end of said plunger is turnably connected, and a coil spring surrounding the upper end portion of said tappet and the lower end

5 portion of the stem of said poppet valve and connected at its lower end to said tappet and at its upper end to said valve stem, with said spring expanded for holding the upper end of said tappet against the lower end of said valve stem, and said valve-closing cam being arranged to engage said lower cross bar, when said poppet valve is upon its seat, for drawing down said yoke and said tappet a slight distance against the tension of said spring, for seating said valve firmly upon its seat under tension of said spring.
